UPHOLSTERY CONSTRUCTION

Albert M. Bank, Jersey City, N. J., assignor to
Sylvia Bank, Jersey City, N. J.

Application December 31, 1936, Serial No. 118,537

2 Claims. (Cl. 155—179)

This invention relates to upholstery construction. It is particularly directed to an upholstered resilient support for a chair, seat, sofa, or the like articles.

5 An object of this invention is to provide an upholstered resilient support of the character described, having a highly improved soft edge construction including strip springs attached to the frame and being arched or bent back to provide 10 a resilient edge for the support.

Yet another object of this invention is to provide in a spring support of the character described, means for interlocking the arched springs to the foundation spring.

15 Yet another object of this invention is to provide a strong and durable upholstered resilient support of the character described, which shall be relatively inexpensive to manufacture, easy to assemble, comfortable in use, which may be incorporated into a large variety of upholstered 20 articles of furniture, and which shall yet be practical and efficient to a high degree.

Other objects of this invention will in part be obvious and in part hereinafter pointed out.

25 The invention accordingly consists in the features of construction, combinations of elements, and arrangement of parts which will be exemplified in the construction hereinafter described, and of which the scope of application will be indicated in the following claims.

30 In the accompanying drawings, in which are shown one of the various possible illustrative embodiments of this invention,

Fig. 1 is a top plan view of an upholstered 35 resilient support embodying the invention, with parts broken away to show the interior construction;

Fig. 2 is an enlarged cross-sectional view taken on line 2—2 of Fig. 1;

40 Fig. 3 is a rear view of my improved resilient support, with parts broken away to show the interior construction;

Fig. 4 is a view similar to Fig. 1, but illustrating a modified form of the invention;

45 Fig. 5 is a perspective view of one of the strip springs used in carrying out my invention;

Fig. 6 is a view similar to Fig. 1, but illustrating a further modified form of the invention;

Fig. 7 is an enlarged, cross-sectional view taken 50 on line 7—7 of Fig. 6;

Fig. 8 is a detailed view taken on line 8—8 of Fig. 7;

Fig. 9 is a perspective view of a piece of covered wire used in the form of the invention disclosed in Fig. 6;

Figs. 10 and 11 are perspective views of strip springs embodying the invention;

Fig. 12 is a view similar to Fig. 6, but illustrating a further modified form of the structure shown in Fig. 6; and

Fig. 13 is a cross-sectional view taken on line 13—13 of Fig. 12.

Referring now in detail to the drawings, 10 designates a resilient or cushioned upholstered support, embodying the invention, here shown 10 for the purpose of illustration in the form of a chair back, although it will be understood that the invention may be embodied in seats or backs for chairs, sofas, or the like articles. The support 10 comprises a frame 11 made of wood or 15 other suitable material and having a top portion 12 and side portions 13. Attached to the underside of the frame 11 is webbing 14 supporting a plurality of foundation springs 15. In Figs. 1 and 2 there is shown, for the purpose 20 of illustration, a one-piece webbing of textile fabric, for example, burlap, although any suitable support for the foundation springs 15 may be employed, such as interwoven strip webbing or metal strips. The foundation springs 15 are 25 shown in the drawings as of the hour glass shape, although it will be understood that any coil foundation springs may be employed.

Attached to the frame 12 at the margins thereof are inner and outer sheets 17, 18 forming a 30 casing 19 filled with padding or stuffing 20 of any suitable kind. An outer covering 21 may be placed over the casing sheet 18 and a covering 22 may be supplied to cover the webbing 14. The foundation springs 15 are interposed 35 between the webbing 14 and the padded casing 19 as shown in Fig. 2 of the drawings.

It will be noted that the foundation springs 15 are arranged in parallel rows. As shown in Fig. 1 of the drawings, the outer convolutions 40 of adjacent foundation springs are clipped together by clips 22 at the point of tangency. Elongated parallel wires 23 disposed between adjacent rows of springs, are also clamped by the clips 22 whereby to form the foundation springs 45 into a unit. Clips 22a and connecting wires 23a may also be supplied on the outer sides of the unit.

In accordance with my invention and for the purpose of providing a soft edge for the spring 50 support, and for reducing the amount of stuffing necessary in the support, there are attached to the top portion 12 of the frame 11, a plurality of spaced, similar strip springs 25. As shown in Fig. 5 of the drawings, each strip spring 25 is 55

made of a flat, thin, elongated, resilient piece of steel and is formed with a plurality of longitudinally spaced openings 26 at one end 30 thereof, and with a plurality of spaced, alternating, longitudinal and transverse slots 27 and 28 adjacent the other end 33 thereof. The strips 25 are normally flat. In Fig. 5 the strip is shown in the position it assumes when incorporated into a spring support or cushion.

10 One end 30 of each strip spring 25 is attached as by a nail or other fastening means 31 to the underside of the portion 12 of the frame. The nail 31 passes through one of the openings 26. The spring 25 is then arched or bent back and the outer end 33 thereof is placed beneath one of the wires 23 and in alignment therewith and beneath adjacent portions of the outer convolutions of a pair of adjacent foundation springs 45. The wires 23 are each provided with inwardly or 15 downwardly humped or offset portions 36 extending through one of the openings 27 in a spring 25.

It will be noted that the offset portions 36 on the parallel wires 23 are in alignment. A transverse wire 40 passes through the offset portions 25 and beneath the outer ends 33 of the springs 25 for interlocking said springs with the wires 23 and hence with the foundation springs. The outer ends 41 of the wire 40 may be bent around 30 adjacent strips 25 to prevent longitudinal shifting of said wire. It will be noted that the springs 25 press outwardly on the stuffed portion or casing 19 of the cushion forming what is termed a soft edge. Chair backs made with 35 spring supports shown in Figs. 1 and 2 of the drawings are comfortable in use because the use of the springs 25 reduces the amount of stuffing necessary at the top edge of the chair back. The spring strips may be quickly and easily 40 assembled with the foundation spring unit.

In Fig. 4 there is shown an upholstered resilient support 10a having soft edges on two sides at right angles to one another. One side may be constructed as shown in Figs. 1, 2 and 3 45 of the drawings. The spring strips 25 of the other side being at right angles to the wires 23 receive the offset portions 36 in one of the transverse slots 28. By providing both transverse and longitudinal slots in the strip 25 said strip 50 may be used in both positions shown in Fig. 4 of the drawings. By providing a plurality of openings 26 and a plurality of slots 27 and 28, the arch or curvature of the member 25 may be adjusted to suit the particular requirement. Furthermore, the end 30 of the spring 25 may be 55 attached either to the outer side or the underside of the frame 12 depending upon the design of the chair.

In Figs. 6 and 7 of the drawings, there is 60 shown a chair back 10b embodying the invention. As shown in said figures, there is attached to the frame 11 a plurality of parallel, flat, supporting steel strips 45 on which are mounted foundation springs 46. The outer convolutions of the foundation springs are formed with integral inwardly offset portions 47. A plurality of strip springs 25, such as shown in Fig. 5 of the drawings, or 47, shown in Fig. 10, may be incorporated into the chair back 10b, one end being attached to the frame and the other end pressing outwardly against the inner side of the stuffed casing portion 19 of the chair back. The outer end of the strip spring en-

gages the outer convolution of the foundation spring 46 and receives the offset portion 47 in a longitudinal slot formed at the outer end thereof. Springs 47 or 25 may be supplied for each side of each foundation spring, as shown in Fig. 6. A piece of covered wire, such as shown in Fig. 9, may be inserted within each offset portion below the strip spring and twisted, as shown at 50 in Fig. 7, to lock the strip spring to the foundation spring. If desired, an elongated piece of covered wire 51, shown in Fig. 9, may be passed through the aligned offset portions 47 in said foundation springs, as shown at 52 in Fig. 6 of the drawings. The wire 51 may comprise a metal core 54 with an outer covering 55 of paper or fabric. Ordinary electric insulated wire may also be used to interlock the foundation springs 46 to the strip springs connected thereto.

In Fig. 12 of the drawings is disclosed a chair 20 back 10c embodying the invention, and in which are incorporated strip springs 55 shown in Fig. 11 of the drawings. The strips 55 have transverse slots 58 at the outer ends thereof. They are attached to the frame 11 as described here- 25 fore. They are located, however, between the foundation springs and are not connected to the foundation springs. The outer ends of the strips 55 are interconnected by a piece of corrugated wire 60 formed with a plurality of off- 30 sets 61. An adjacent offset is inserted through the slot 58 of each strip 55 and interlocked by a piece of twisted wire or cord or insulated wire, such as shown in Fig. 9, the twisted wire being designated by numerals 65 in Fig. 13.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new my desire to secure by Letters Patent:

1. In a chair back, a frame, web means attached to said frame, foundation springs supported on said web means, a stuffed casing attached to said frame and overlying said frame, said foundation springs being interposed between said web means and said casing, a wire interconnecting a plurality of said foundation springs and being formed with an offset portion, a strip spring attached at one end to said frame and being flexed backwardly into curved shape, said strip spring being formed with an opening receiving said offset portion, and a member passing through said offset portion to lock said strip spring to said wire.

2. In upholstery construction, a frame, web means for said frame, foundation springs on said web means, a plurality of strip springs each attached at one end to said frame and bent into curved shape, wires connecting the outer convolutions of said foundation springs and having offset portions, said strip springs having openings receiving said offset portion, and a member passing through said offset portions and engaging said strip springs.

ALBERT M. BANK.
